United States Patent

Des. 241,859

Patented Oct. 12, 1976

241,859

INDICATOR OF ROOM OCCUPANCY

Nestor A. Kmicikewicz, 916 Cardero St., Vancouver 5,
British Columbia, Canada

Filed June 19, 1975, Ser. No. 588,441

Claims priority, application Canada May 27, 1975;
Great Britain June 7, 1975

Term of patent 14 years

Int. Cl. D19—08

U.S. Cl. D96—12 R

FIG. 2

FIG.1

FIG. 4

FIG.3

FIG. 6

FIG.5

FIG. 1 is a front elevational view of an indicator of room occupancy showing my new design;

FIG. 2 is a top plan view of FIG. 1;

FIG. 3 is a right side view of FIG. 1, the left side elevational view being a mirror image thereof;

FIG. 4 is a bottom plan view of FIG. 1;

FIG. 5 is a rear elevational view of FIG. 1; and

FIG. 6 is a cross-sectional view, taken along the line 6-6 of FIG. 1.

FIGS. 1 and 5 are shaded for color contrast.

I claim:

The ornamental design for an indicator of room occupancy, substantially as shown and described.
